The ornamental design for an air circulation fan as shown and described.

DESCRIPTION

FIG. 1 is a front, top perspective view of an air circulation fan showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a top perspective view thereof, showing the air circulation fan in a state of use;

FIG. 9 is an enlarged detail view taken from portion 9 of FIG. 2;

FIG. 10 is an enlarged detail view taken from portion 10 of FIG. 3;

FIG. 11 is an enlarged detail view taken from portion 11 of FIG. 4;

FIG. 12 is an enlarged detail view taken from portion 12 of FIG. 6; and,
